UNITED STATES PATENT OFFICE

167,877

DOLL

Lenna D. Ballew, Chicago, Ill.

Application September 18, 1951, Serial No. 16,679

Term of patent 14 years

(Cl. D34—4)

To all whom it may concern:

Be it known that I, Lenna D. Ballew, a citizen of the United States, residing at Chicago, State of Illinois, have invented a new, original, and ornamental Design for Doll, of which the following is a specification, reference being had to the accompanying drawing, forming a part hereof.

Fig. 1 is a front view of a doll, showing my new design;

Fig. 2 is a side view of the doll shown in Fig. 1; and

Fig. 3 is a back view of the doll shown in Fig. 1.

I claim:

The ornamental design for a doll, as shown.

LENNAD. BALLEW.
